UNITED STATES PATENT OFFICE.

JOHN C. GOULD, OF CHICAGO, ILLINOIS.

NAIL-PLATE FEEDER.

SPECIFICATION forming part of Letters Patent No. 292,300, dated January 22, 1884.

Application filed August 3, 1883. (No model.)

To all whom it may concern:

Be it known that I, JOHN C. GOULD, a citizen of the United States, residing in Chicago, in the county of Cook and State of Illinois, 5 have invented a new and useful improvement in Nail-Plate-Feeding Machines, of which the following is a specification.

This invention relates to the devices for feeding the nail-plate supporting-rod in nail- 10 plate-feeding machines; and it consists in the novel construction and combination herein-after set forth.

In said drawings, which form a part of this specification, Figure 1 is a side view of that portion of the machine to which my invention relates. Fig. 2 is an end view of the same. Fig. 3 is a transverse vertical section. Fig. 4 is a bottom view, and Fig. 5 is a longitudinal vertical section.

20 In the drawings, A represents the bracket whereby the rod-grippers are supported. It is secured to the machine at the end thereof not shown. B is the rod whereby the nail-plate is carried, fed, and placed in position for the cutters. C C' are the gripping devices, acting upon the said rod and actuating it intermittently toward the knives, and D is the stop-rod whereby the grippers are swung upon their pivot to move the rod forward in its 25 course. D' is the set-screw whereby the length of the stroke or throw caused by the stop-rod is changed when desired, and D² is the spring by which the rod D' and the grippers are kept together. The throw of the grippers is limited by the bolt g, passing through the bracket A, and an arm, G, attached to one of the grippers. These parts do not differ from corresponding parts of machines heretofore constructed.

30 The grippers are oscillated upon a common pivot, c, held by set-screws a, passing through the end of the fork a' of the bracket A into the ends of the pivot. Between the grippers is an intermediate piece, E, also encircling the 35 pivot c, provided at its lower end with a wedge, e, which comes in contact with the angling faces c' of the gripper ends. At its upper end said intermediate piece fits over a round knob or projection, c², upon the gripper C, so that 40 it is rigidly held at that point, except against

oscillation on said knob c². The grippers and this intermediate piece are held together by a bolt, F, fitting closely in the gripper C, and engaging with a thread therein. At its other end the bolt has a hemispherical head setting 55 in a corresponding recess in the gripper C. The opening in the intermediate piece through which the bolt passes is enlarged to give room to a spring, f, encircling the bolt and tending to keep the grippers apart. To give this 60 spring plenty of room, the recess in which it lies may be extended into one of the grippers, as shown. The upper end of the intermediate piece serves to support the plate-rod, as is clearly indicated in Figs. 1 and 2. 65

The operation of the device is as follows: When the bracket, which is oscillated with the other parts of the feeder, swings toward the knives, the stop-rod comes in contact with a stop in the ordinary manner, and arrests the 70 movement of the intermediate piece in which it is stepped, as already stated. This forces said wedge to spread the lower ends of the grippers, and this results, of course, in the seizure of the plate-rod by the upper ends of 75 the grippers, and also in giving said upper ends an additional or farther movement, which carries said rod forward the width of a nail-blank. The retreat of the bracket in the opposite direction releases the wedge end of the 80 intermediate piece from the influence of the stop-rod and said end returns to its normal position, thereby allowing the upper ends of the grippers to spread from each other and release the plate-rod. When the grippers are 85 next actuated to seize the rod, they take hold thereof at a point farther back, and so on until the plate is entirely cut up.

The purpose of the spherical head of the bolt F and its recess in the gripper C' is that said 90 gripper may rock on said bolt as a pivot to the extent permitted by the looseness of its fit upon the pivot c. Of course this may be permitted by other forms which will allow such motion. I adopt the form shown because 95 it is easily manufactured.

It will be noticed that the intermediate piece, E, also loosely encircles the pivot c. This enables the said intermediate piece to move sufficiently to cause the grippers to take hold of 100

the plate-rod, and is of course essential, because the wedging movement must be independent of the grippers.

I claim—

5 1. The combination, with the grippers, of the intermediate wedge-piece and the stop-rod actuating said wedge-piece, substantially as specified.

10 2. The combination, with the grippers, of the intermediate piece having a wedge for spreading the lower ends of the grippers, and

a spring, *f*, for spreading the upper ends of the grippers, substantially as specified.

3. The combination, with the grippers, of the intermediate piece, *E*, for opening and 15 closing the grippers and forming a support for the plate-rod, substantially as specified.

JOHN C. GOULD.
